UNITED STATES PATENT OFFICE.

EDWARD E. GAINER, OF NEW YORK, N. Y., ASSIGNOR TO ZENAS U. DODGE, OF NEW YORK, N. Y.

ICE-MAKING APPARATUS.

1,014,140.

Specification of Letters Patent.

Patented Jan. 9, 1912.

Application filed March 15, 1911. Serial No. 614,731.

To all whom it may concern:

Be it known that I, EDWARD E. GAINER, a citizen of the United States, and resident of New York, in the county and State of 5 New York, have invented certain new and useful Improvements in Ice-Making Apparatus, of which the following is a specification.

The objects of this invention are to simplify the construction and increase the efficiency of ice making apparatus and to provide simple and novel means for supporting the ice holding receptacles or freezing cans against displacement in the refrigerant tank. These and other objects will appear and be better understood from the following description taken in connection with the accompanying drawings, in which:

Figure 1 is a detail partly in elevation 20 and vertical section showing one embodiment of my invention. Fig. 2 is a similar view on the line 2—2 of Fig. 1 looking in the direction of the arrow. Fig. 3 is a detail plan view of one of the freezing cans.

Referring to the drawings 5 indicates the header for the refrigerant fluid. This header, as usual, extends into the tank 6 and is connected to and forms the outlet of a suitable pump. The pump and its connection with the header 5 are well known in the art, and for that reason I do not deem it necessary to show this arrangement, since a statement to the effect that the pump draws the refrigerant 7 from the tank 6 and 30 discharges the same through the header 5 will be sufficient to enable those skilled in the art to carry out my invention.

The can 8 is interiorly provided with the freezing tubes 9, the upper ends of which 40 are closed as shown at 10 and lie a trifle below the surface of the water 11 when the same partially fills the can as shown in the drawings. The lower ends of the tubes 9 extend through the bottom 12 of the can 45 and are surrounded by bushings 13 which serve to protect the lower ends of the tubes and form a tight joint to prevent the entrance of the refrigerant fluid into the can. The tubes 9 receive stand-pipes 14 which 50 communicate with the header 5 and extend to points adjacent to the closed ends 10 of the tubes 9.

A common support for the header and can comprises a pair of metallic straps 14' 55 and 15. The middle portions 16 of the

straps embrace the header 5 and terminate in radial extensions 17 secured together in any preferred manner, such as by rivets 18. The radial extensions 17 of each strap are in vertical alignment and terminate in angularly disposed feet 19 and 20. The lower feet 19 bear upon the bottom 21 of the tank and the upper feet 20 bear upon the central portion of the bottom 12 of the can. By the provision of this form of support, the header 5 will be held in spaced relation to the bottom 21, whereby the tank 6 may be drained and thoroughly cleaned and also the can 8 is supported above and in spaced relation to the header 5, whereby the refrigerant fluid may more readily circulate through the tubes 10 and completely cover the bottom 12.

The stand-pipes 14 are approximately the same in length as the tubes 10, and since the latter are but a trifle less than the length of the can it will be seen that these members will coöperate to prevent the can from toppling and center the same on the feet 20.

In use a quantity of water sufficient to 50 cover the upper ends 10 of the tubes is placed in the can 8. Suitable tackle is then connected in openings 22 in the top portion of the can, after which the can is elevated and swung over the tank 6 and guided into 55 alignment with the stand-pipes 14, and then lowered to the position shown in Figs. 1 and 2. During the operation of freezing the refrigerant 6 is circulated through the header 5 and stand-pipes 14 by the pump 90 in the manner before described. After the water 11 has been frozen the can is removed 95 from the tank and inverted. A suitable thawing agent may then be introduced into the tubes 10 and around the exterior of the 100 can, whereupon the cake of ice will fall therefrom. By constructing the tubes 9 in the manner shown the openings formed in the cake by the tubes will be bottomed, whereby the openings may be readily filled 105 with distilled water.

Having thus described the invention what I claim as new and desire to secure by Letters-Patent is:

1. In an ice making apparatus, in combination, a refrigerant tank, a header arranged in the tank and spaced from the bottom thereof, a stand-pipe connected to the header, a can spaced from the header, a freezing tube opening at one end through 110

the bottom of the can and closed at its opposite end and adapted to receive the stand-pipe, and a common support for the header and can adapted to hold the same in their 5 relative positions.

2. In an ice making apparatus, in combination, a refrigerant tank, a header arranged therein, two stand pipes connected to the header and extending vertically therefrom, a can, two freezing tubes arranged vertically in the can and each opening at one end through the bottom of the can and being closed at its upper end, said tubes being arranged to receive the stand pipes 10 and to coöperate with the stand pipes to hold the can upon its support, and a support for the can arranged between said stand pipes.

3. In an ice making apparatus, in combination, a refrigerant tank, a header arranged therein, a stand-pipe connected to the header, a can, a freezing tube opening at one end through the bottom of the can and closed at its upper end, said tube being 15 adapted to receive the stand-pipe and co-

operating with the same to prevent displacement of the can with respect to the header, and a common support for the header and can serving to hold the same in spaced relation to each other.

4. In an ice making apparatus, in combination, a refrigerant tank, a header arranged therein, a stand-pipe connected to the header, a can, a freezing tube opening at one end through the bottom of the can and closed at its upper end, said tube corresponding in length approximately to the length of the stand-pipe and adapted to receive the same and coöperating therewith to prevent displacement of the can with respect to the 30 header, and a support for the header bearing on the bottom of the can and holding the same in space relation to the header.

In testimony whereof I affix my signature in presence of two witnesses.

EDWARD E. GAINER.
